UNITED STATES PATENT OFFICE.

ALOIS HELFENSTEIN, OF VIENNA, AUSTRIA-HUNGARY.

ELECTRIC FURNACE.

1,082,196.

Specification of Letters Patent. Patented Dec. 23, 1913.

Application filed April 16, 1913. Serial No. 761,636.

To all whom it may concern:

Be it known that I, ALOIS HELFENSTEIN, a citizen of the Swiss Republic, residing at 50 Bastiengasse XVIII, Vienna, Austria-Hungary, have invented a new and useful Improvement in Electric Furnaces, of which the following is a specification.

My invention relates principally to improvements in that class of closed electric furnaces with upper electrodes in which charging chutes are disposed above joint hearths so the charging material forms the shortest electric connection between the electrodes.

The invention consists of the arrangement of the chutes between the upper pairs of the vertical electrodes whereby from these chutes the charging for and through the chutes the removal of the gases from the two adjacent electrode chambers is effected.

The intermediate spaces formed by the charging-chutes, and through which the electrodes pass, are utilized for charging purposes; the openings for the electrodes being tight, and the electric melting region in the effective zone of the electrodes is readily and quickly accessible, without interfering with the continuity of charging the material or of removal of the gases. In order to serve both classes of chutes from the same platform, special feed-tubes or troughs are arranged suitably in these intermediate spaces between the charging-chutes.

In the annexed drawing, in which the object of the invention is shown conventionally, Figure 1 is a three-phase furnace with three vertical electrodes, partly in elevation, partly in lengthwise section. Fig. 2 is a plan of the device; and Fig. 3 is a cross section thereof.

A is the electric furnace, B₁, B₂, B₃, B₄ charging chutes arranged above along the entire width of the furnace, which form the hoppers C₁, C₂, C₃ for the insertion of the electrodes.

E₁, E₂, E₃ are the vertically-hanging electrodes.

Charging the furnace is effected in the usual manner through the hoppers D₁, D₂, D₃, D₄. Charging of the hoppers C₁, C₂, C₃ is effected through separate pipes G₁, G₂, G₃, G₄, G₅, G₆. The electrode hoppers C₁, C₂, C₃ taper downward; and for the insertion and

regulation of the electrodes have only a small slot, which permits the passage of but little material. Thus the opening for the insertion of the electrode will be kept gas-tight, and the gases compelled to pass off through the charging-chutes. These gases can be led off in the usual manner through the regular off-take, or exhausted laterally from the charging-chutes by the pipes F₁, F₂, F₃, F₄.

The charging-chutes have lateral man-holes M₁, M₂ through which the charging can be observed as it takes place, and when necessary the operations in the furnace regulated (Fig. 3).

Where the gases are exhausted laterally from the charging chutes (Fig. 2) the exhaust-pipes F₁, F₂ terminate in the collecting-pipes S₁, S₂, which lead off the gases for further use.

What is claimed is:

1. In a device of the kind described, a hearth, a series of charging chutes arranged above said hearth, a series of electrodes suspended above said hearth and alternating with said chutes, and means to charge material into the spaces between said chutes and electrodes.

2. In a device of the kind described, a hearth, a series of charging chutes arranged above said hearth in spaced relation thereto, the lower ends of said chutes flaring laterally and being spaced from each other to provide electrode receiving openings, and electrodes suspended in said openings in spaced relation to said chutes.

3. In a device of the kind described, a hearth, a series of charging chutes arranged above said hearth in spaced relation thereto, the lower ends of said chutes flaring laterally and being spaced from each other to provide electrode receiving openings, electrodes suspended in said openings in spaced relation to said chutes, and supplemental chutes carried by the first mentioned chutes and arranged to charge the spaces between said electrodes and first mentioned chutes.

In testimony whereof I affix my signature in presence of two witnesses,

ALOIS HELFENSTEIN.

Witnesses:

AUGUST FUGGER,
IGNAZ KNORFALMACHER.
